SCREW-ON WIRE CONNECTOR

William G. Schinske, Sycamore, Ill., assignor to Ideal Industries, Inc., Sycamore, Ill., a corporation of Delaware

Application January 27, 1959, Serial No. 54,335

Term of patent 14 years

(Cl. D26—10)

I claim:

The ornamental design for a screw-on wire connector, as shown.
